UNITED STATES PATENT OFFICE.

HERMAN D. KELLER, OF COLDWATER, MICHIGAN, ASSIGNOR TO KELL-OIL HEATER COMPANY, OF COLDWATER, MICHIGAN, COMPOSED OF HERMAN D. KELLER, MARY J. KELLER, HERMAN J. KELLER, LOUIS B. KELLER, JOHN G. KELLER, MARY A. MORRIS, CATHERINE C. PARISIAN, AND FRANK H. KELLER.

ORCHARD HEATER.

1,419,570.

Specification of Letters Patent. Patented June 13, 1922.

Application filed May 6, 1921. Serial No. 467,501.

To all whom it may concern:

Be it known that I, HERMAN D. KELLER, a citizen of the United States, residing at Coldwater, in the county of Branch and 5 State of Michigan, have invented a new and useful Orchard Heater, of which the following is a specification.

This invention relates to heaters and is more particularly directed to an orchard 10 heater for preventing injury to an orchard by frosts or severe cold spells.

In employing heaters of this type which are adapted to burn oil, considerable difficulty is experienced in supplying the proper 15 quantity of air for an economical consumption of fuel while eliminating smoke and soot.

Likewise, difficulty has been experienced in properly conducting air to the heater 20 which air is distributed afterwards to the orchard so that this heated air will not interfere with the consumption of the fuel and cause smoking of the burner.

An object of this invention is the provision of a new and improved means in the 25 burner by which the air to be heated is carried to the center of the device and then evenly distributed to the exhaust gases of the burner.

Another object of this invention is the provision of a new and improved means in the 30 burner by which the air is heated preliminarily as it enters and is conducted to the center of the burner and before it is discharged into the exhaust gases in the chimney.

A further object of the invention is the provision of a new and improved means by 35 which the air is preliminarily heated before it is discharged into the exhaust gases of the burner and which heated air also acts as a heating means for the distributor of the air.

A still further object of the invention is the provision of a new and improved means 40 by which the air for the burner is directed away from the center of the fuel tank when the tank is full of oil.

Another object of the invention is the provision of a new and improved means by 45 which the air for the burner is directed towards the center of the fuel tank when the oil does not quite fill the receptacle.

The invention will be best understood from a consideration of the following detailed de-

scription taken in connection with the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claims.

In the drawing:—

Fig. 1 is a view in elevation partly in section showing my improved burner.

Fig. 2 is a cross section through the line 2—2 of Fig. 1 disclosing a plan view of the top of the fuel container.

Fig. 3 is a cross section along the line 3—3 of Fig. 1, disclosing a plurality of intake tubes and their common outlet.

Fig. 4 is a cross section along the line 4—4 of Fig. 1, disclosing a bottom plan view of the removable cap for the chimney.

Fig. 5 is an enlarged view in section showing a detail of the fastening means for the cover as applied to the fuel receptacle.

The invention comprises a fuel tank, a top for the tank, an intake chamber or member for delivering air to be heated by the burner, a chimney for the burner, a distributing chamber which is in communication with the air intake and the chimney, and a removable top to prevent rain from entering the chimney and also for delivering the heat to the atmosphere in a downward direction.

In the drawings, 1 designates a tank or fuel container filled with oil and provided with a top 2 which has a central opening 3 and a flange 4 projecting upwardly from the periphery of the opening. The top 2 is secured in any manner to the fuel receptacle 1, but as is shown in the drawings, it may be attached by means of a downwardly turned flange 2' integrally formed on the periphery of the top 2 and cemented to an annular beveled portion on a ring 5. To augment the above securing means, spaced lugs 5' projecting outwardly from the ring 5 are fastened by means of bolts to lugs 6 similarly spaced on and projecting outwardly from the flange 2' of the top.

An air intake chamber or member 7 which is cylindrical in form engages the flange 4 on the top 2 for holding the intake in position

2
above the fuel tank. The intake 7 is provided with a plurality of conduits 8 disposed horizontally of the intake and meeting at a common center. An opening or port 9 5 formed in the upper portion of the intake where these conduits meet is bordered by a flange 10 upon which is mounted a perforated, air distributer 11 having a closed top 12, perforations 13, and a port 14 concentric 10 with the port 9 in the intake 7. The intake conduits 8 have openings 15 in the outer cylindrical shell of the intake 7 in order that exterior air may pass through these conduits to the center of the chamber and upwardly through the ports 9 and 14 into the distributing chamber 11.

15 A chimney 17 is removably mounted upon a flange 16 on the upper edge of the cylindrical intake 7. A top 18 mounted upon the top of the chamber 17 is spaced therefrom by 20 means of the feet 19 which are secured to the top and have a bent portion 20 cooperating with the top of the chimney to hold the top in place.

25 The top of the fuel container is provided with openings 21 and 22 for the admission of air and fuel to the container. Flanged tubes 23 are secured on the top in alinement with these openings. A cover or lid 24 is 30 pivoted to this flanged tube for closing or opening the ports 21 and 22 to the fuel container. Beneath the port 21 and secured to the under side of the top 2 is a semi-circular plate 25 which is adapted to direct air entering 35 the port 21 away from the center of the oil chamber when the chamber is full of oil. A bent tube or conduit 26 having the portion 27 extending towards the center of the fuel container is secured to the bottom of 40 the top 2 and in alinement with the port 22 for admitting air towards the center of the fuel chamber when the container is nearly full.

45 The conduits 8 are so spaced from each other in the air intake that they provide passages 28 between the fuel tank 1 and the chimney 17.

The operation of my device is as follows. Fuel oil is poured into the fuel container 1 50 through either of the ports 21 or 22 in any quantity sufficient to fill the container. One of the ports 21 or 22 is kept open to admit air to the tank 1 for maintaining combustion in the burner. The oil is then ignited 55 by dropping waste or any combustible material into the fuel container, thereby igniting the oil on the surface, and the smoke and gases which are formed in the combustion of the oil pass upwardly through the passages 60 28 around the conduits 8 and upwardly through the chimney 17, and then out into the atmosphere. As the exhaust gases pass around the conduits 8, these conduits are heated and likewise the distributer 11. The 65 air in these two members being heated will

rise, pass through the perforations 13 in the air distributer 11, and then into the exhaust gases which are escaping from the chimney.

It will be seen that as the air passes through the conduits 8 and the distributing 70 chamber 11, it will have no detrimental effect upon the burner itself because this air will not affect the quantity of the air drawn into the burner.

If it be desired to extinguish the burner, 75 it will be only necessary to close either of the ports 21 or 22 so that no more air may be admitted to the chamber 1.

Instead of the slip joint between the air intake 7 and the cover 2, the air intake may 80 be pivoted directly to the cover and slidably thereon. It will be seen that by this arrangement, the air intake 7 and chimney 17, which are held in vertical alinement on each other, may be turned upon the pivotal connection between the air intake and the cover 2, in order to provide a larger opening for filling the receptacle 1 and also make it possible to more easily clean the interior of the heater.

90 What is claimed is:—

1. A heater, comprising a fuel receptacle, a cover for said receptacle provided with an opening centrally disposed therein, an air intake member mounted on the cover, an air 95 distributer mounted centrally of and in communication with the air intake, and a chimney mounted on the air intake member and surrounding the air distributer.

2. A heater, comprising a fuel receptacle, 100 a cover for said receptacle provided with an opening centrally disposed therein, an air intake mounted on the cover, an air distributer mounted centrally of the air intake, said air intake being provided with a plurality of horizontally disposed passages having a common inlet communicating with the air distributer, and a chimney disposed on the air intake and concentric with the air distributer.

105 3. A heater, comprising a fuel receptacle, a cover for said receptacle provided with air inlets, an air intake chamber mounted on the cover, an air distributer mounted on and in communication with said air intake, said air intake comprising a plurality of passages intersecting at a common point, a passage providing a communication between the air intake and the air distributer at the point of intersection of the passages, a chimney disposed on the intake and concentric with the air distributer, and a passage providing communication between the fuel receptacle and the chimney.

110 4. A heater, comprising a fuel receptacle, a cover for said receptacle provided with an opening centrally disposed therein, a chimney located above said fuel chamber and in open communication with the same, 115 an air distributer mounted concentrically 120

within the chimney, and means for directing air to the center of the chimney directly into the air distributor.

5. A heater, comprising a fuel receptacle, 5 a cover for said receptacle, means for admitting air to said receptacle, means for directing said air away from the center of said receptacle, a chimney located above said receptacle, means for admitting air to the 10 center of said chimney, and means for distributing said air in all directions to the chimney.

6. A heater, comprising a fuel receptacle, a truncated and centrally perforated cover, 15 a flange surrounding the aperture, an air intake chamber disposed above said cover and removably mounted on the flange, a perforated tubular member having a closed top mounted on the air distributor and in 20 open communication with the same, and a chimney provided with a heat retainer disposed on one end, mounted on the air intake chamber.

7. A heater, comprising a fuel receptacle, 25 a chimney located on said receptacle, a passage providing a communication between the receptacle and the chimney, an air intake member mounted within said passage, and an air distributor mounted on the air 30 intake member.

8. A heater, comprising a fuel receptacle, a chimney located on said receptacle, a passage providing a communication between the receptacle and the chimney, an air intake 35 mounted within said passage, and a distributor mounted above the air intake, said air intake being provided with a plurality of passages and adapted to direct air to the center of the chimney and to the air 40 distributor.

9. A heater, comprising a fuel receptacle, a chimney located on said receptacle, a passage providing a communication between the receptacle and the chimney, an air intake 45 mounted within said passage, a distributor mounted above the air intake, means for admitting air to the fuel receptacle, and means for directing said air away from the center of the receptacle.

10. A heater, comprising a fuel receptacle, 50 a cover for said receptacle having a centrally disposed opening therein, a chimney mounted on said cover, and means for directing air to the center of said chimney comprising a plurality of tubular members meeting at a common point, a perforated tubular member having one end closed and the other end in open communication with an opening at the point where the tubular members meet. 55

11. A heater comprising a fuel receptacle adapted to maintain a partial combustion of the fuel, a chimney in communication with the fuel receptacle, and means for distributing heated fresh air to the burning 60 gases from the fuel receptacle at a point in the chimney above the fuel receptacle. 65

12. A heater comprising a fuel receptacle, a chimney in communication with the fuel 70 receptacle, an air distributor spaced from the chimney, an air intake member arranged below and in communication with the distributor for supplying heated air to said distributor, said air distributor having a series of perforations adapted to supply heated 75 air to the chimney.

13. A heater, comprising a fuel receptacle, a cover for said receptacle, an air intake chamber mounted above said cover, an air distributor mounted on said air intake, 80 and a chimney mounted on the air intake, said air intake being adapted to direct air to the center of the heater directly into the air distributor.

14. A heater comprising a fuel receptacle, 85 a chimney mounted above said receptacle for the escape of the products of combustion arising therefrom, an air intake formed of a plurality of conduits located above the receptacle in the path of the ascending 90 products of combustion, and heated thereby, said air intake collecting air from the outside and after being heated discharging it into the chimney.

In testimony that I claim the foregoing 95 as my own I have hereto affixed my signature.

HERMAN D. KELLER.
